(57) **CLAIM**

The ornamental design for a sequential lights delineator, as shown.

DESCRIPTION

FIG. 1 is a top perspective view of a sequential lights delineator embodying the new design.

FIG. 2 is another top perspective view of the sequential lights delineator shown in FIG. 1.

FIGS. 3 and 4 are side elevation views of the upper portion of the sequential lights delineator shown in FIG. 1.

FIG. 5 is a front side elevation view of the upper portion of the sequential lights delineator shown in FIG. 1.

FIG. 6 is a rear side elevation view of the upper portion of the sequential lights delineator shown in FIG. 1; and,

FIG. 7 is a top plan view of the sequential lights delineator shown in FIG. 1.

The broken lines shown in the drawings represent portions of the sequential lights delineator that form no part of the claimed design. The broken line break line seen in FIGS. 3-6 identifies where the top portions are cut from and forms no part of the claimed design.
